UNITED STATES PATENT OFFICE.

NEWTON K. BOWMAN, OF NORTH LAWRENCE, OHIO.

MINING-MACHINE BIT.

Application filed August 17, 1920. Serial No. 404,108.

To all whom it may concern:

Be it known that I, NEWTON K. BOWMAN, citizen of the United States, residing at North Lawrence, in the county of Stark and 5 State of Ohio, have invented certain new and useful Improvements in Mining-Machine Bits, of which the following is a specification.

This invention relates to an improved bit 10 for mining machines and has as one of its principal objects to provide a bit employing a stock which may, if desired, be permanently fixed to the links of an ordinary mining machine chain and wherein a demountable cutting tooth will be provided to accomplish the actual cutting operation.

A further object of the invention is to provide an arcuate cutting tooth so that the tooth will be adapted to withstand shearing 20 strain thereon and wherein the tooth may be constructed of hardened material for resisting wear.

A still further object of the invention is to provide a tooth having a curved cutting 25 edge whereby the tooth will operate with a shearing action and wherein the sloping sides of the tooth will curve with said cutting edge to provide clearance for shavings.

And the invention has as a still further 30 object to provide a tooth which may be readily reversed end for end.

Other and incidental objects will appear hereinafter.

In the drawing:

35 Figure 1 is a perspective view of my improved bit,

Figure 2 is a sectional view particularly showing the mounting of the tooth,

40 Figure 3 is a rear perspective view showing the cutting tooth in detail,

Figure 4 is a view similar to Figure 2, showing a slight modification of the invention, and

45 Figure 5 is a transverse sectional view taken on the line 5—5 of Figure 4, looking in the direction of the arrows.

Bits as now manufactured are formed of relatively soft material with the result that the bits soon become dulled. To then 50 sharpen the bits it is necessary to remove the bits from the endless chain of the mining

machine and the services of a blacksmith are usually required to accomplish the sharpening operation. Obviously, this not only results in expense but considerable delay. 55 However, it has been found impracticable, due to the size of the bits, to form said bits of hard material since this would involve an expense out of proportion to the advantage gained. The present invention, therefore, 60 seeks to overcome these various difficulties.

Referring particularly to Figures 1, 2 and 3 of the drawings, I employ a stock 10 which is designed to supplant the usual bits of a mining machine chain and at its inner end 65 portion is formed for connection to the links of said chain in the customary manner. If desired, the stock 10 may be permanently fixed to the chain. At its outer end the stock is formed with a beveled face and at 70 its forward edge is provided with an arcuate beveled seat 11 substantially V-shaped in cross section and having diverging sloping faces 12. In conjunction with the stock I employ an arcuate cutting tooth 13. As particularly shown in Figure 3, the tooth is longitudinally curved to conform to the curvature of the seat 11 of the stock and is substantially V-shaped in cross section, having angularly disposed sides 14 which are 75 curved to seat flat against the beveled faces 12 of said seat so that the apex of the seat abuts the crotch between said sides from end to end of the tooth. The tooth will thus be rigidly supported throughout its entire 80 length by the stock and formed on the tooth at its forward face is a medial longitudinally curved or arcuate cutting edge 15 disposed opposite the apex of the seat 11. The cutting edge 15 extends from end to end of the tooth and, as will now be noted, the tooth 85 is formed with beveled divergent end faces which respectively define at each end of the tooth a substantially V-shaped cutting prow 16 terminating in a cutting point and having sharp side edges. From the cutting edge 15, the sides 14 slope to provide oppositely directed beveled faces 17 and due to the curvature of said sides, these faces are curved 90 longitudinally to conform to the curvature of the cutting edge. Formed in the sides of the tooth at their free edges are medial

notches 18 and fitting over the tooth to embrace the outer end portion of the stock is a clamp 19 the sides of which extend through said notches fitting close against the sides 5 of the stock, it being observed in this connection that the sides 14 of the tooth slightly overhang the stock. At its forward end, the clamp is formed to fit the contour of the tooth bearing over said tooth medially there- 10 of and threaded through the rear end of the clamp is a set screw 20 adjustable to engage the rear edge of the clamp for firmly bind- ing the tooth in position. Thus, as will be seen, the tooth will be rigidly connected to the stock while, at the same time, the tooth 15 may be readily detached. Consequently, should it become necessary, the tooth may be easily removed and a new tooth substituted therefor, eliminating the work and delay of 20 detaching the stock 10 from the chain of the mining machine. Due to the size of the tooth, it may, without undue expense, be readily formed of hardened material for re- sisting wear and, also, this feature makes it 25 readily possible to carry a supply of extra teeth with each machine.

Attention is now directed to the fact that when the cutting tooth is clamped in place the end portions thereof extend forwardly 30 from the stock 10 so that the cutting prow at one end of the tooth is exposed at the outer end of the stock. Thus, the cutting point of said prow will, when the tooth is in operation, lead the cutting edge 15 and due to the sharpness of said cutting point, 35 said point will operate to readily sink or cut into the working face of the mine, permitting the cutting edge 15 to function. As the tooth is advanced the sloping cutting 40 edges at the sides of said prow will, as will be seen, operate against the mine face with a shearing action for loosening or cutting the coal in advance of the edge 15, thus fa- cilitating the work of said edge, while the 45 curved faces 17 of the sides of the tooth will operate to pry or force the coal cut by the cutting edges of the prow inwardly toward the inner end of the tooth at opposite sides of the edge 15. The edge 15 will, therefore, 50 in effect, work against loosened coal and since said edge is curved rearwardly away from each of the cutting points of the tooth, this edge will accordingly also operate against the coal with a shearing action for cutting 55 the coal. Where a straight cutting edge is employed upon a cutter of this nature, a marked tendency is exhibited to merely mash or press into the coal so that the cutter not only cuts slower but also a great 60 deal more force is required to drive the cutter. However, by employing a curved cutting edge to extend in the rear of a sharp cutting point flanked by diverging cutting edges, as exemplified in the tooth of the

present invention, the cutting action of the tooth is pronounced so that the greater portion of the coal actually cut falls away from the tooth in small lumps. The creation of what is commonly known as "bug dust" is thus greatly reduced and it has been found 70 in practice that the coal cut can be utilized for fuel purposes. Furthermore, attention is directed to the fact that owing to the longitudinal curvature of the tooth, the tooth will better resist strain thereon inci- 75 dent to engagement of either of its cutting points with the work and, as will be appreciated, when one of said points has become dulled, the tooth may simply be reversed end for end. In this connection it is to 80 be noted that the cutting edge 15 provides, in effect, a prolongation of the cutting points of the prows of the tooth so that as the ends of the tooth wear away, the pres- 85 ence of said edge will serve to maintain said cutting points sharp. Also, since the faces 17 of the sides of the tooth curve lat- erally inward from the diverging cutting edges of the prows of the tooth, these edges 90 will also be maintained sharp as the ends of the tooth wear away. Consequently, the tooth will be self sharpening in marked de- gree. Stress upon the exposed end of the tool incident to engagement thereof with the work will, of course, tend to shift the 95 tooth inwardly upon the stock. However, due to the curvature of the seat 11 of said stock, the tooth cannot shift longitudinally of the stock in either direction without ris- 100 ing toward the forward edge of the stock. Consequently, even a slight longitudinal movement of the tooth will cause the tooth to jam between its seat and the clamp 19 and thus eliminate any looseness of the tooth. As will be appreciated, this feature 105 provides an arrangement whereby the tooth will at all times be held firmly upon the stock while accidental displacement of the tooth will be prevented.

In Figures 4 and 5 of the drawings, I 110 have illustrated a slight modification of the invention. In this modification, I employ a stock 21 which, like the stock 10 is adapted for connection to a mining machine chain to supplant the ordinary bits thereon. This 115 stock is beveled at its outer end and at its forward edge is provided with an arcuate substantially V-shaped seat 22 having con- verging sloping faces 23. In conjunction with the stock I provide an arcuate tooth 24. This tooth is, as particularly shown in Figure 5, substantially V-shaped in cross section, being formed with converging lon- 120 gitudinally curved sides 25, and is adapted to fit the seat of the stock seating flat there- in. Thus, the sloping faces 23 of said seat 125 will rigidly support the sides of the tooth while the apex between said sides will,

throughout its entire length, abut the crotch of the seat so that the tooth will be rigidly sustained from end to end thereof. The tooth is formed with divergent beveled ends 5 which define, at each end of the tooth, a prow having a pair of cutting points 26 from which extend sloping side cutting edges and between these pairs of cutting points extend longitudinally curved or arcuate cutting edges 27 provided by the free edges of the sides 25 of the tooth. As will be appreciated, the cutting points 26 are adapted to function in a manner similar to the cutting points 16 of the tooth disclosed 10 in the preferred form of the invention while the cutting edges 27 will function in a manner similar to the cutting edge 15. Formed in the sides of the tooth 26 are medial notches 28 and engaging over the tooth to 15 embrace the stock 21 is a clamp 29, the sides of which engage in said notches extending close to the sides of the stock, the sides 25 of the tooth overhanging the stock. At 20 its forward end, the clamp 29 is bent to form a rib 30 fitting the crotch between the sides of the tooth and threaded through the inner end of the clamp is a set screw 31 adjustable to engage the inner edge of the stock for tightly binding the tooth thereon. Thus, 25 the tooth will be effectively connected to the stock while, at the same time, the tooth may, when desired, be easily removed.

As will be seen, this modified structure possesses many structural features in common with the preferred form of the invention and in view of the previous explanation as to the operation of the preferred construction, further description in connection with the modified structure is believed 30 unnecessary in this regard.

Having thus described the invention, what is claimed as new is:

1. A bit for mining machines including a stock having an arcuate substantially V-shaped seat, an arcuate substantially V-shaped tooth for said seat provided in the sides thereof with notches, a clamp engaging over the tooth to embrace the stock and having the sides thereof extending through 45 said notches, and means adjustable upon the clamp to coact with the stock for binding the tooth against said seat.

2. A reversible tooth for mining machines comprising a body portion of substantially concavo convex form in cross section with its opposite ends converging in the direction of the convex side of the tooth to form diverging work engaging points.

3. A reversible tooth for mining machines comprising a segmental body portion having its opposite ends beveled to form terminal work engaging points and its side edges between said points formed with notches for the reception of a fasten-

ing device whereby the tooth may be secured in position on the stock of a mining machine.

4. In a mining machine, a substantially crescent shaped cutting tooth V-shaped in cross section and having its opposite ends 70 converging in the direction of the convex side of the tooth and terminating in diverging working points, the tooth being reversible end for end and the diverging walls of the tooth forming an arcuate cutting edge 75 extending between said points.

5. In a mining machine, the combination with a stock for attachment to a chain link and having an arcuate seat, an arcuate double ended cutting tooth engaged in said seat, and means engaging the tooth between its ends and connecting the tooth with the stock whereby the tooth will be clamped in engagement with the stock for the major portion of the length of the tooth and longitudinal movement of the tooth will operate to jam the tooth between 80 said means and its seat, the tooth being reversible end for end upon the stock and the stock forming a backing for the ends 90 of the cutting tooth.

6. In a mining machine, a stock having a beveled end and a concave seat, a reversible tooth of substantially crescent shape engaging said seat and having its opposite 95 ends beveled to conform to the beveled end of the stock to provide terminal working points, and means carried by the stock and engaging the tooth between the working points thereof for clamping the major portion 100 of the tooth in engagement with its seat to form a backing for said working points.

7. In a mining machine, the combination with a stock having a concave seat in one longitudinal edge thereof, of a substantially crescent shaped tooth engaging said seat and provided with oppositely disposed working points and its side walls formed with notches, and a clamping device 105 encircling the stock and tooth and fitting in said notches for detachably securing the tooth in position on the stock and holding the tooth to its seat for the major portion 110 of the length of the tooth.

8. In a mining machine, the combination with a stock, of a reversible tooth having lateral wings bearing against the stock, and a clamping device engaging the tooth between the ends thereof for rigidly securing the tooth in position on the stock with the lateral wings bearing firmly against said stock throughout the major portion of the length of the tooth to form a backing 120 for the working ends of the tooth.

9. In a mining machine, the combination with a stock, of a reversible tooth having lateral wings, and means engaging the

tooth between the ends thereof for rigidly securing the tooth in position on the stock with the lateral wings bearing firmly against said stock to provide a backing for the working end of the tooth.

10. As a new article of manufacture, a reversible double-ended mining machine bit tooth provided with integral angularly disposed sides having their junction defining a

cutting edge at the forward face of the 10 tooth and formed with beveled end edges sloping rearwardly away from the ends of said cutting edge to define cutting points at the ends of the tooth as well as to provide clearance behind said cutting points. 15

In testimony whereof I affix my signature.

NEWTON K. BOWMAN. [L. S.]
